COMBINED SEAT AND TABLE OR THE LIKE

Donald J. Eilert, Salem, Oreg.

Application May 23, 1955, Serial No. 36,163

Term of patent 7 years

(Cl. D33—14)

FIG.1

FIG.4

Fig. 1 is a side elevation of a combined seat and table or the like showing my new design;

Fig. 2 is a top plan view;

Fig. 3 is a rear elevation; and

Fig. 4 is a front elevation thereof.

I claim:

The ornamental design for a combined seat and table or the like, as shown.
